UNITED STATES PATENT OFFICE.

WILLIAM H. BRITTON, OF MILFORD, AND OLNEY S. THAYER, OF BELLINGHAM, MASSACHUSETTS; SAID THAYER ASSIGNOR TO SAID BRITTON.

IMPROVEMENT IN CLAMPS.

Specification forming part of Letters Patent No. **151,680**, dated June 9, 1874; application filed May 15, 1874.

To all whom it may concern:

Be it known that we, WILLIAM H. BRITTON, of Milford, county of Worcester and State of Massachusetts, and OLNEY S. THAYER, of Bellingham, in the county of Norfolk, State of Massachusetts, have invented a certain new and useful Improvement in Clamps, of which the following is a description sufficiently full, clear, and exact to enable any person skilled in the art or science to which our invention appertains to make and use the same, reference being had to the accompanying drawing, forming a part of this specification, in which—

Figure 1 is an isometrical perspective view of our improved clamp; Fig. 2, a view of the sliding bracket; Fig. 3, a view of the coupler or ferrule; and Fig. 4, a view of the bolt.

Like letters indicate corresponding parts in the different figures of the drawing.

Our invention relates to that class of clamps which are used by manufacturers of doors, sashes, and like articles in setting the joints which have been glued, or prior to pinning or fastening the frame together; and consists in a novel construction and arrangement of the parts, as hereinafter fully set forth and claimed, by which a cheaper and more effective implement for this purpose is produced than is now in common use.

In Fig. 1, A is the body or beam of the clamp; B D, the brackets; C, the slide; F, the lever, and L the ferrule or coupler. The brackets B D are provided with runlets U and projections b b, Fig. 2, which projections slide in the grooves J J, Fig. 1, and operate to keep the clamps upon the face-plate T. The lever F is provided with the cam-shaped end E and serrated edge G, and is hung in the bracket D upon the journals R. The slide C has a tail piece or slotted guide, I, which works on the stud i; and there is a link, H, attached to the bracket D, and through which the lever G passes. The ferrule L is provided with side apertures M P, and also with outwardly-projecting flanges Q Q, which enter the grooves J J when the thimble is in use. The bracket B has a stud, K, projecting from its runlet-face U, which stud drops into the apertures S in the face-plate T, as the bracket is moved along the plate, the bracket being loosely fitted

to the plate for this purpose, the bracket D having a similar stud, and being held upon the plate in a similar manner. The object of the ferrule L is to enable the clamp to be lengthened to any desired extent by coupling on another beam similar to A, by means of the pins N, Figs. 1 and 4, which fit the apertures M P, Fig. 3, and extend into the apertures S, when in use, thus holding the beams together.

From the foregoing the nature and operation of our invention will be readily obvious to all conversant with such matters.

The bracket D being arranged secured on the beam A, as shown in Fig. 1, the bracket B is moved along the face-plate a sufficient distance to admit the article to be clamped or acted upon between the face of the slide C and the face of the bracket B, and the stud K allowed to drop into one of the apertures S. The lever G is then depressed, bringing the slide C forcibly against the article to be clamped, the lever being held down by the link H in a manner which will be plainly apparent without a more explicit description.

By removing the bracket B, and arranging the bracket D centrally on the beam A, the clamp may be used for a lifting-jack.

The clamp will also be found useful for many purposes other than those specified.

It will be obvious that any number of apertures may be made in the plate T; also, that any number of the beams may be coupled together by thimbles or couplers L, the bracket B being placed in a proper position upon one of the beams before they are coupled.

Having thus described our invention, what we claim is—

The extensible clamp described, consisting of the brackets B, having the stud K, the bracket D, provided with the slide C and serrated cam-lever F, and the beam A, having the grooves J J and apertures S S, combined to operate substantially as and for the purpose specified.

WILLIAM H. BRITTON.
OLNEY S. THAYER.
